UNITED STATES PATENT OFFICE.

JOSEPH R. DUNBECK, OF ROCHESTER, NEW YORK, ASSIGNOR TO WM. H. NICHOLLS CO., INC., OF BROOKLYN, NEW YORK, A CORPORATION OF NEW YORK.

MOLDING MACHINE.

Application filed April 25, 1924. Serial No. 708,935.

To all whom it may concern:

Be it known that I, JOSEPH R. DUNBECK, a citizen of the United States, and resident of Rochester, in the county of Monroe and State of New York, have invented certain new and useful Improvements in Molding Machines, of which the following is a specification.

The invention is illustrated as applied to 10 a molding machine of the type shown in Patent No. 1,472,807, dated November 6, 1923. In machines of this type the flask, after being filled with sand, is jolted to pack the sand in around the pattern, and after 15 the jolting operation the sand is pressed or squeezed under a heavy pressure. After the squeezing operation the pattern is withdrawn from the mold and then the flask, with the complete mold therein, is lifted from the 20 machine. These flasks are sometimes quite heavy and the removal of them from the molding machine is quite a laborious operation.

The main object of this invention is to 25 provide means whereby after the mold making operation is finished and the pattern withdrawn from the mold, the flask may be lifted from the flask holding frame and rolled from the molding machine.

Another object of the invention is to provide a molding machine with a manually 30 operable mechanism by means of which the flask, with the completed mold therein, may be slightly raised from the flask holding frame and then rolled out of or away from the molding machine.

In the drawings, Fig. 1 is a side elevation partly in vertical section, of a molding machine with the invention applied thereto;

Fig. 2 a vertical sectional view taken on the line 2—2 of Fig. 1;

Fig. 3 an end elevation of the lower portion of the machine partly in vertical section, the section being approximately on the line 3—3 of Fig. 1;

Fig. 4 a horizontal sectional view on the line 4—4 of Fig. 2, the flask and pattern holding frame and plate being removed;

Fig. 5 a detail sectional view of one side 50 of the flask elevating members;

Fig. 6 a detail perspective view of one end of the flask holding frame showing one of the flask elevating members applied thereto; and.

Fig. 7 a detail sectional view of a portion 55 of the flask elevating and conveying means.

Referring to the various parts by numerals, 1 designates the base of the machine. This base carries a vertical cylinder 2 which is open at its upper end and closed at its lower end by a horizontal wall 3 which forms part of the base. On one side of the base is formed a socket 4 in which is mounted an upstanding rigid post 5 on the upper end of which is rotatably mounted a swing- 60 ing frame arm 6. The frame arm 6 carries the upper pressure head 7. In the free end of the frame arm 6 is formed an open jaw 8 which is adapted to receive the upper end of an upstanding rod 9 mounted in a socket 70 10 carried by the base diametrically opposite the socket 4 so that the upward thrust on the head 7 will be taken up in part through the rod 9. When the pressure head 75 is swung into position over the flask the jaw 8 receives the rod 9 and fits between the thrust nut and collar carried by said rod.

In the cylinder 2 is fitted a large squeezing piston 11. The upward movement of the squeezing piston is limited by headed bolts 80 12. A small vertically arranged cylinder 13 is formed at the center of the squeeze piston, the upper end of this cylinder being open and the lower end of said cylinder being formed by the bottom wall of the squeeze 85 piston. A short distance above the bottom of this cylinder is formed an exhaust port 14. Mounted in the smaller cylinder 13 is a jolt piston 15. This piston is provided with a cross wall 16 a short distance upwardly 90 from its lower end. Extending through this cross wall is an air supply pipe 17 which leads out through the upper end of said piston and to an air control valve mounted on the base 1.

Formed integral with the upper end of the jolt piston is a jolt-and-squeezing head 18. The lower end of this head is adapted to rest on the upper end of the squeeze piston. Formed on the head 18 are four radial 100 diagonal arms 19 which carry vertically depending tubular sockets 20. On the upper surfaces of the head 18 and the arms 19 are formed ribs 21. These ribs form a horizontal support for a pattern plate holding frame 22, said frame being open and rectangular. The pattern holding frame is secured to the ribs 21 with its center directly 105

over and coincident with the center of the jolt piston. The pattern plate 23 is rigidly secured to the upper side of the holding frame.

5 In the ends of the base are formed vertical sockets 24 in which are mounted vertical plunger rods 25. The upper ends of these rods are connected to the end bars of the flask supporting frame 26. The end bars are connected together by front and rear bars so that the flask supporting means is an open rectangular frame. This flask supporting frame surrounds the pattern holding frame and in its normal, or at rest, 10 position is in substantially the same horizontal plane as said holding frame. On the front and rear bars of the flask holding frame are formed upstanding parallel flanges 26^a on the upper surfaces of which 15 are secured flask receiving rails 27. Flask 27^a rests on these rails. The flanges 26^a and the rails 27 are slightly shorter than the flask so that the end walls of the flask project slightly beyond the ends of the rails 20 27, shown clearly in Fig. 1. When the flask holding frame is in its lowermost position the pattern plate fits in between the rails 27 and forms the bottom of the flask. In 25 this position of the parts the flask holding frame is at rest on the upper ends of the sockets 20 so that the said frame and the flask partake of the jolting movement of the head 18.

The flask supporting frame is provided at 30 each corner with a depending rigid guiding pin 28 and these pins slide in the sockets 20 carried by the head 18. These guide pins assist in accurately guiding the pattern plate holding frame during the pattern 35 drawing operation. The plunger rods 25 are notched to receive locking dogs 29 mounted on rock shafts 30, said shafts being connected by means of a link and crank arms so that said locking dogs may be simultaneously released from the plunger rods 40 by means of a foot lever 31 connected to one of the rock shafts 30.

The supply of compressed air to the jolt and squeeze pistons is controlled by a valve 45 50 32 mounted on the base in convenient position for manipulation by the operator.

The operation of forming a mold in a machine of the type herein described is as follows:

55 The flask is placed in position on the pattern plate and on the flask holding frame. The flask is filled with sand and the valve turned to permit air to pass through pipe 17 to lift the jolt piston, the head 24 and 60 the flask carrying frame, until the exhaust port 14 is uncovered. The jolting operation is continued until the sand is properly packed around the pattern. After the jolting operation the air valve is rotated to supply air through the pipe 33 under the

squeeze piston. The pressure head 7 is so positioned that when the squeezing operation is completed the locking dogs 29 drop into the notches in the plungers 25. When the pressing operation is complete the air valve is turned to exhaust air from beneath the piston 11. This permits the pistons, the head 18, the pattern plate holding frame and the attached pattern plate, to drop to the position shown in Fig. 1, but the dogs 29 hold the flask carrying frame in its upper position. The pattern plate holding frame and the pattern plate are guided in their downward drawing movement by the four guide pins 28 and by the squeeze piston 10 15 20 25 30 35 40 45 50 55 60 65 70 75 80 85 raised position. The bars 34 and the rollers 41 form in effect a track over which the flask travels.

The flask elevating means is mounted wholly on the flask supporting frame and moves up and down with it. It is manifest that the pattern must be withdrawn from the mold before the mold can be rolled rearwardly out of the machine.

10 While the invention is shown as applied to a certain type of molding machine, it is manifest that it may be applied to any form of molding machine wherein the pattern is withdrawn from the mold or the mold raised off the pattern.

In order to lock the flask in proper position with respect to the pattern plate and to withdraw said locking means when the pattern is withdrawn from the mold, the 20 head 18 is provided with upstanding pins 43 which are arranged to reciprocate through vertical apertures 44 in the flask holding frame. The flask is formed with lugs 45 directly in line with the apertures 44 in the flask holding frame. When the flask holding frame is in its lower position the pins 43 extend up through the apertures in the lugs 45, thereby properly positioning the flask with respect to the pattern plate. 30 When the pattern is withdrawn, as shown in Fig. 3 the locking pins 43 are withdrawn from the lugs 45 and the flask is then free to be moved on the rollers 41 rearwardly out of the machine.

35 What I claim is:

1. A molding machine comprising a flask support, a pattern drawing mechanism, a track means, and means to shift the track means upwardly to lift the flask free from 40 the flask support and position it for movement over the track means outwardly away from the machine.

2. In a foundry machine, a flask support, shiftable flask-lifting and conveying means 45 provided with anti-friction flask-engaging elements, and means for raising one end of the said conveying means to raise the flask from its support and thereby permit the flask to move outwardly and downwardly 50 over the antifriction elements away from the machine.

3. A molding machine comprising a pattern plate holding means, a flask supporting means, means for holding the flask supporting means to withdraw the pattern from the mold, and shiftable flask lifting and conveying means for raising the flask free from the flask supporting means and positioning it for outward movement away from 60 the machine over said conveying means.

4. A molding machine comprising a pattern plate holding means, a flask supporting means, means for forcing the pattern plate holding means and the flask supporting means upwardly to squeeze and compact

the sand in the flask, means for holding the flask supporting means in an elevated position while the pattern holding means is lowered to withdraw the pattern from the mold, and manually operable means mounted on the flask supporting means for lifting the flask from the flask supporting means, said lifting means comprising a pair of lifting and conveyor bars carrying a series of rollers adapted to engage the end 70 walls of the flask, said bars in their elevated position inclining rearwardly and downwardly.

5. A molding machine comprising a pattern plate holding means, a flask supporting means, means for forcing the pattern plate holding means and the flask supporting means upwardly to squeeze and compact the sand in the flask, means for holding the flask supporting means in an elevated position while the pattern holding means is lowered to withdraw the pattern from the mold, and manually shiftable flask lifting and conveying means mounted on the flask supporting means for raising the flask free from 80 the flask supporting means and positioning it for outward movement from the machine over the conveying means.

6. A molding machine comprising a pattern plate holding means, a flask supporting means, means for forcing the pattern plate holding means and the flask supporting means upwardly to squeeze and compact the sand in the flask, means for holding the flask supporting means in an elevated position while the pattern holding means is lowered to withdraw the pattern from the mold, a shiftable flask lifting and conveying means carried by the flask supporting means normally below the flask, and means 90 for raising the forward end of the said conveying means to raise the flask from its supporting means and thereby permit the flask to move rearwardly and downwardly on the conveyor away from the molding machine.

7. A molding machine comprising a pattern plate holding means, a flask supporting means, means for forcing the pattern plate holding means and the flask supporting means upwardly to squeeze and compact the sand in the flask, means for holding the flask supporting means in an elevated position while the pattern holding means is lowered to withdraw the pattern from the mold, a shiftable flask lifting and conveying means normally below the flask, and means for raising the forward end of the said conveying means to raise the flask from its supporting means and thereby permit the flask to move rearwardly and downwardly on the conveyor away from the molding machine.

8. A molding machine comprising a pattern plate holding means, a flask supporting 115

- means, means for holding the flask supporting means while the pattern plate holding means is lowered to withdraw the pattern from the mold, track means normally below the flask, and means to elevate the track to engage and lift the flask free from its support, the track being adapted to have the flask move thereover outwardly away from the machine.
- 10 9. A molding machine comprising a pattern plate holding means, a flask supporting means, means for holding the flask supporting means while the pattern plate holding means is lowered to withdraw the pattern from the mold, flask lifting and conveying track means normally below the flask, and manually operable means to elevate the track means into engagement with the flask and incline said track means, whereby the flask is lifted from its support and permitted to move over said inclined track means downwardly and outwardly away from the machine.
- 15 10. In a foundry machine, a flask support, a flask lifting and conveying track normally below the flask, and means to elevate and incline the track to engage and lift the flask from its support, said track being provided with anti-friction elements over which the flask is adapted to move downwardly and outwardly away from the machine when the track is elevated and inclined.
- 20 11. A molding machine comprising a pattern plate holding means, a flask supporting means, means for holding the flask supporting means while the pattern plate holding means is lowered to withdraw the pattern from the mold, a shiftable flask lifting and conveyor track, and means to shift the track upwardly whereby the track engages and lifts the flask free from its support and positions it for outward movement away from the machine over the track.
- 25 12. A molding machine comprising a pattern plate holding means, a flask supporting means, means for holding the flask supporting means while the pattern plate holding means is lowered to withdraw the pattern from the mold, a shiftable flask lifting and conveyor track, and means to shift the track upwardly and incline it, whereby the flask is engaged by the track and lifted free from its supporting means and positioned for downward and outward movement away from the machine over the inclined track.
- 30 13. A foundry apparatus comprising a flask support, a flask conveyor track located adjacent the flask support, means to support said track and hold it against lateral movement away from the flask support, and means to cause a relative vertical movement between the flask support and the conveyor track to cause the conveyor track and a flask on the flask support to be brought into en-

gagement with each other to separate the flask from its support and to transfer the flask directly to the conveyor track for lateral movement over and along said track away from the flask support.

14. A foundry apparatus comprising a flask support, a pattern drawing mechanism, a flask conveyor track located adjacent the flask support, and means to cause a relative vertical movement between the flask support and the conveyor track to cause the conveyor track and a flask on the support to be brought into engagement with each other and the flask thereby separated from the flask support and transferred directly to the conveyor track in position to be moved laterally over and along the conveyor track above the flask support outwardly from the apparatus.

15. A foundry apparatus comprising a flask support, a mold squeezing mechanism, a flask conveyor track located adjacent the flask support, means to support said track and hold it against lateral movement away from the flask support, and means to cause a relative vertical movement between the flask support and the conveyor track to cause the conveyor track and a flask on the flask support to be brought into engagement with each other and the flask thereby separated from the flask support and transferred directly to the conveyor track in position to be moved laterally over and along the conveyor track above the flask support outwardly from the apparatus.

16. A molding machine comprising a mold squeezing mechanism, a flask support fixed laterally with relation to the mold squeezing mechanism, a flask conveyor mounted on the machine adjacent the flask support, and means to cause a relative vertical movement between the flask support and the conveyor to cause the conveyor and a flask on the flask support to be brought into engagement with each other and the flask thereby separated from the flask support and transferred directly to the conveyor in position to be moved laterally over and along the conveyor above the flask support outwardly from the machine.

17. A molding machine comprising a mold squeezing mechanism, a flask support fixed laterally with relation to the mold squeezing mechanism, a flask track mounted upon the machine adjacent the flask support, means to support the track and hold it against lateral movement away from the flask support, and means to cause a relative vertical movement between the flask support and the track to cause the track and a flask on the flask support to be brought into engagement with each other and the flask thereby separated from the flask support and transferred directly to the flask track in position to be moved laterally over and along the track

above the flask support outwardly from the machine.

18. A molding machine comprising a mold squeezing and jolting mechanism, a pattern drawing mechanism, a flask support fixed laterally with relation to the pattern drawing mechanism, a flask conveyor track mounted on the machine adjacent the flask support, and means to cause a relative vertical movement between the flask support and the conveyor track to cause the conveyor

track and a flask on the flask support to be brought into engagement with each other and the flask thereby separated from the flask support and transferred directly to the conveyor track in position to be moved laterally over and along the conveyor track above the flask support outwardly from the machine. 15

In testimony whereof I hereunto affix my 20 signature.

JOSEPH R. DUNBECK.
